UNITED STATES PATENT OFFICE

EDMOND PHILIPONEAU, OF LEVALLOIS-PERRET, FRANCE, ASSIGNOR TO SOCIETE ANONYME DES ANCIENS ETABLISSEMENTS HOTCHKISS & CIE., OF ST. DENIS, SEINE, FRANCE, A JOINT-STOCK COMPANY OF FRANCE

HIGH-SPEED RECIPROCATING MECHANISM

Application filed March 29, 1929, Serial No. 351,025, and in France May 16, 1928.

This invention relates to a device for reducing the rebound of members of mechanisms reciprocating at high speed, said rebound being produced when a moving part 5 strikes against another part of said mechanism. The device can be applied to any mechanism but it is particularly adapted in the case of automatic quick firing fire-arms in which the rebound frequently results in 10 faulty working and may even cause accidents.

The invention broadly consists in fitting a hammer piece to the member whose rebound it is desired to reduce, said hammer piece 15 moving with the member when said member effects its normal travel in the mechanism, but continuing its movement when said member is suddenly stopped by an impact with another part of the mechanism and 20 striking said member in the opposite direction to that in which the rebound tends to be produced, thus considerably reducing the rebound, and even completely eliminating it.

Said hammer piece can be made advantageously in the form of a slide-block lodged in a recess of the moving member in such a manner that it can accomplish a predetermined stroke, said side-block being held in its idle position by a spring and striking 30 the end of the recess when said member is suddenly brought to a standstill.

The invention has been illustrated diagrammatically and purely by way of example in the accompanying drawing, 35 wherein:

Fig. 1 is a diagrammatic view in longitudinal section of the device according to the invention.

Fig. 2 is an assembly view showing the 40 device fitted to an automatic fire-arm.

In this drawing, the piston 1 of the mechanism of a quick firing automatic fire-arm, operated by the explosion gases for example. This piston 1 as is known, has a reciprocating 45 movement, being driven rearwards, in the direction of the arrow 2, by the pressure of the gases from the barrel of the gun and forwards, in the direction of the arrow 3, by a return spring 1^a.

When the piston moves forwards (arrow

3) its shoulder 4 strikes against a fixed part 4^a of the mechanism, at the end of its stroke. Probably, owing to the resilience of the material, the resultant violent impact causes the piston to rebound, that is to say, to move 55 rearwards whereby, in the case of quick-firers, a number of incidents may occur, thus percussion may be prevented or a partial unlocking produced, in the case of a hangfire for example. 60

The present invention, which provides a means for considerably reducing and even completely eliminating the rebound, consists in housing in a recess 5 in said piston, a hammer-piece 6 which can accomplish a predetermined stroke within said recess. The hammer-piece 6 is held in the position shown in the drawing by a spring 7. When the piston accomplishes its normal displacement in either direction, said hammer-piece moves 70 with it. But when, towards the end of the forward stroke of the piston, the said impact occurs, the hammer-piece 6 continues its forward movement in the direction of the arrow 3 and, just as the rebound of the piston 75 is about to occur, strikes the end 5^a of the recess 5, thus giving the piston 1 a blow in the opposite direction to that of the rebound, which will thus be considerably reduced.

The weight and stroke of the hammer-piece 6 as also the strength of the spring 7 must be calculated by duly allowing for the weight and speed of the piston. 80

In Fig. 2, the cocking-piece 8 and its spring 9 have been shown in their relative positions 85 with respect to the piston 1.

The hammer-piece may have any shape and any method of fitting the same to the piston may be used, said hammer-piece differing in both these respects from the example given above. Similarly, not only may the invention be applied to the piston but also to all the other moving parts of a quick-firer mechanism, actuated by the explosion 90 gases, or of any other type.

Still more generally, the invention may be advantageously applied to any mechanism having parts moving at high speed and subjected to impacts which may cause a rebound 100.

liable to produce defective operation of said mechanism.

It will, of course, be understood that the invention has only been described in a purely explanatory but by no means limitative manner and that it may be subjected to various modifications of detail without departing from the spirit thereof.

I claim:

- 10 In a device for reducing the rebound of a displaceable member of a high speed mechanism after impact with another, fixed member of said mechanism, the combination of a hammer-piece received in a recess of said displaceable member and capable of displacement in said recess, and a spring bearing against the end of an opening formed in said hammer-piece and against one end of said recess, said spring serving to hold the hammerpiece at the rear of the recess, but allowing said hammer-piece to continue its displacement in said recess after said displaceable member has been suddenly arrested, whereby said hammer-piece will strike 20 against the front end of said recess to prevent the displaceable member from rebounding as a result of the blow caused by its being suddenly arrested by the fixed member of the mechanism.

EDMOND PHILIPONEAU.
